STOVE

Joseph E. Taylor, De Land, Fla.

Application April 5, 1938, Serial No. 200,196

7 Claims. (Cl. 110—7)

This invention relates to a stove or heater, and an object of the invention is to provide a stove or heater so constructed as to burn sawdust, a mixture of sawdust and oil, or sawdust and other combustible material, or other materials alone or in combination with each other.

The invention together with its objects and advantages will be best understood from a study of the following description taken in connection with the accompanying drawings wherein:

Figure 1 is a vertical sectional view through the stove or heater.

Figures 2 and 3 are horizontal sectional views taken substantially on the lines 2—2 and 3—3 respectively of Fig. 1.

Referring to the drawings by reference numerals it will be seen that the stove or heater, in the preferred embodiment thereof comprises a substantially frusto conical casing or drum 5 provided adjacent the bottom thereof with an internal ledge or shoulder 6 that support a false bottom 7 of annular form and having a central opening 1' so that ashes can fall through into ash pit 8. Below the false bottom 7 the drum or casing 5 presents an ash pit 8 to which access is had through the medium of a door 9. Door 9 is provided with a suitable damper indicated generally by the reference numeral 10 to control the draft.

Disposed above the false bottom 7 and suitably spaced upwardly therefrom is a conical baffle 11 that is provided on the lower end of a tubular conduit 12.

The tubular conduit 12 at the upper end thereof is provided with retention hooks 13 which engage over the upper end of a perforated tubular conduit 14 that is of greater diameter than the tube 12 and is disposed circumjacent the tube 12 as shown.

Conduits 12 and 14 are retained in suitably spaced relation through the medium of upper and lower series of lugs 15 provided on the periphery of the conduit 12 as shown.

The conduit 14 is disposed at the axial center of the casing 5 and at its lower end terminates short of the conduit 12 and is provided with an integral conical baffle 16 that is spaced vertically from the conical baffle 11 as shown.

The conduit 14 serves as a retainer for the lid 17 provided for the top of the casing 5 through the medium of radially extending lugs 18 that project from the upper end of the conduit 14 and engage a reversely curved vertically disposed flange 19 provided at the edge of the lid 17 de-

fining an opening 20 through which the upper end of the conduit 14 extends.

The conduit 12 and associated parts are also supported within the casing 5 through the medium of hanger brackets 21 that at one end are riveted or otherwise secured to the cone 11 and at the upper end are provided with hooks 22 that engage an internal ledge 23 provided on the peripheral wall of the casing or drum 5 as clearly shown in Figs. 1 and 3.

Obviously the conduit 12 serves as a flue for the escape of smoke and gases while the conduit 14 serves as a conduit for the escape of gas, the gas passing into the space between the baffles 11 and 16, and between the flue 12 and conduit 14 to discharge at the top of the conduit 14. Hooks 13 are pressed inwardly toward the flue tube 12 to clear the upper edge of the tube 14 when it is desired to remove the tube from the casing 5, tube 14 and its associated conical baffle 16 being removable, or withdrawable from the casing 5 at the top of the latter upon removal of the cover or lid 17.

Also the flange 19 rimming the opening 20 in the lid 17 is provided at diametrically opposite sides thereof with slots 24 so that when it is desired to remove the lid or place the lid on the casing 5 without disturbing the conduits 12 and 14 said lid is rotated so as to align the slots 24 with the lugs 18 whereupon the lid may then be shifted axially relative to the tube 14 incidental to the placing of the lid on the casing 5 or the removal of the lid therefrom.

In connection with the above it will be noted that the lower edge of the baffle 16 rests on the suspension brackets 21 so that these brackets serve to support baffle 16 and associate tube 14 independently of the lid 17 permitting removal or placement of the lid without disturbing the position of the tube 14 and its integral baffle 16.

The lid 17 has rising therefrom a substantially conical stack 25 the upper end of which merges into a substantially cylindrical extension 26. Preferably lid 17 and stack 25 are mutually separable so that the stack 25 may be removed without disturbing the lid 17, stack 25 positioned on the lid 17 merely resting thereon without positive connection with the lid.

The lid 17 is also provided with any desired number of apertures 27 in order that a poker 50 may be inserted through a selected opening and into the drum or casing 5 for agitating or disturbing the fuel 28 within the casing in a manner to insure a feeding of the fuel, by gravity, toward the bottom 7 of the stove or heater.

The perforations in the sleeve or tube 14 serve to facilitate the passage of accumulated gases into the space between sleeve or conduit 14 and the sleeve or flue 12.

- 5 For the purpose of facilitating combustion within the stack 25 the latter is provided with upper and lower series of perforations 29 and 30 as shown.

The utility and advantages of the invention will be apparent from the following:

The fuel, if a mixture of fuels, is prepared beforehand. The stack 25 is lifted aside after which the top 17 is rotated until the slots 24 in the flange 19 are in alignment with the lugs 18 when the lid 15 17 is then removed from the casing or top 5. The fuel is then placed into the casing, filling the space between a wall of the casing and the conduit or sleeve 14, after which the top or lid 17 is replaced.

20 As shown in Fig. 1, the fuel will pile up on the bottom 7 and between the outer edges of the baffle cone 11, 16 and the peripheral wall of the casing or drop 5. Ignition, by means of a torch, match or lighted paper is produced on the surface of the fuel resting on the false bottom 7. The draft is regulated by the damper 10, and after combustion has proceeded for some minutes the baffles 11 and 16 and flue 12 together with the fuel adjacent to the baffles 11 and 16 as well as the fuel on the

25

30 the spaces 7 and 10 as well as the face of the
false bottom 7 will become intensely hot. When
a sufficient heat has been obtained, the air intake
through the damper 10 is decreased so that the
fire in the fire box 31 provided beneath the cone
or baffle 11 is only sufficiently active to keep that
35 area hot. This lessens the combustion in the fire
box 31 and produces gases which escape upwardly
through the flue 12 and also through the space
between the baffles 11 and 16 and the space be-
tween the flue 12 and conduit tube 14.

40 Ignition of these escaping gases takes place at the top of the flue 12 and sleeve 14, and the gases form within the top of the fuel container are allowed to escape through the opening 20. Combustion of the gas escaping at this point takes
45 place along with the gases escaping between the flue 12 and sleeve 14. The combustion in the stack 25 also completes the combustion of gases passing upwardly and escaping from the flue 12.

It will also be appreciated that as the fuel is consumed at the bottom of the drum 5 the fuel gradually feeds to the bottom 7 and the fire box 31 where combustion takes place.

By removing the lid 17 and the stack 25 the device may be used as a smudge pot.

55 What is claimed is:

1. In a stove of the character described, a casing having a false bottom of annular form provided with a central opening and an ash pit below said false bottom, a pair of vertically spaced conical baffle members arranged above said false bottom and having their peripheries circumferentially spaced inwardly from the peripheral wall of said casing, said baffles being of a diameter greater than the opening in the false bottom and centrally spaced above said opening to prevent discharge of fuel from the casing through the opening, the upper one of said baffles having a perforated tubular member extending upwardly therefrom, and the lower one of said baffles having an imperforate tubular member defining a flue extending upwardly therefrom and arranged within the first mentioned tubular member and circumferentially spaced therefrom.

2. In a stove of the character described, a casting, a pair of concentrically arranged stacks in

the casing including an outer perforate stack and an inner imperforate stack and defining a flue, and a lid for said casing having a flanged opening at the center thereof through which said stacks extend, and the flange rimming the opening in said lid being provided at opposite sides thereof with slots, and the outer stacks having lugs projected from diametrically opposite sides thereof and cooperable with the flange for releasably retaining the lid in position on said casing. 5 10

3. In a stove of the character described, a casing, a pair of concentrically arranged stacks in the casing including an outer perforate stack and an inner imperforate stack and defining a flue, and a lid for said casing having a flanged opening at the center thereof through which said stacks extend, and the flange rimming the opening in said lid being provided at opposite sides thereof with slots, and the outer stack having lugs projected from diametrically opposite sides thereof and cooperable with the flange for releasably retaining the lid in position on said casing, and the inner stack having spring catches mounted on opposite sides thereof adjacent the upper end of the inner stack and engageable with the upper edge of the outer stack for retaining said stacks against casual longitudinal movement relative to one another. 15 20 25

4. In a stove of the character described, a casing, a pair of concentrically arranged stacks in the casing including an outer perforate stack and an inner imperforate stack and defining a flue, and a lid for said casing having a flanged opening at the center thereof through which said stacks extend, and the flange rimming the opening in said lid being provided at opposite sides thereof with slots, and the outer stack having lugs projected from diametrically opposite sides thereof and cooperable with the flange for releasably retaining the lid in position on said casing, and the inner stack having spring catches mounted on opposite sides thereof adjacent the upper end of the inner stack and engageable with the upper edge of the outer stack for retaining said stacks against casual longitudinal movement relative to one another, said casing being provided upwardly from the bottom thereof with an annular internal ledge and suspension means within the casing for the lower ends of the stacks. 30 35 40 45

5. In a stove of the character described, a casing, a pair of concentrically arranged stacks in the casing including an outer perforate stack and an inner imperforate stack and defining a flue, and a lid for said casing having a flanged opening at the center thereof through which said stacks extend, and the flange rimming the opening in said lid being provided at opposite sides thereof with slots, and the outer stack having lugs projected from diametrically opposite sides thereof and cooperable with the flange for releasably retaining the lid in position on said casing, and the inner stack having spring catches mounted on opposite sides thereof adjacent the upper end of the inner stack and engageable with the upper edge of the outer stack for retaining said stacks against casual longitudinal movement relative to one another, said casing being provided upwardly from the bottom thereof with an annular internal ledge, and said stacks having flared lower ends vertically spaced from each other with the flared end of the outer stack above the flared end of the inner stack, suspension brackets secured at one end thereof to the flared end of the inner stack, the other end of the brackets being formed 50
55
60
65
70

to engage said ledge and the flared end of the outer stack seating against said suspension brackets.

6. In a stove of the character described, a casing adapted to contain solid fuel and provided adjacent the bottom thereof with an annular false bottom having a central opening, a conical baffle supported in the casing above the opening of said false bottom and of a diameter greater than the opening to prevent discharge of fuel through the opening, said false bottom and baffles forming a fire box, a flue for said fire box extending upwardly from the apex of said conical baffle, a second conical baffle disposed above the first mentioned conical baffle and vertically spaced therefrom, and a perforated tube extending upwardly from the second conical baffle and disposed about, and in circumferentially spaced relation to said flue.

7. In a stove of the character described, a casing provided adjacent the bottom thereof with an annular false bottom, a conical baffle supported in the casing above said false bottom and defining therewith a fire box, and a flue for said fire box extending upwardly from the apex of said conical baffle, a second conical baffle disposed above the first mentioned conical baffle and vertically spaced therefrom, and a perforated tube extending upwardly from the second conical baffle and disposed about, and in circumferentially spaced relation to said flue, and spring catches adjacent the upper end of said flue and engageable with the upper end edge of the perforated tubular member and coacting therewith for retaining said baffles and tubular members assembled.
